Primary Examiner — Messina L Smith

CLAIM

The ornamental design for a chef knife set, as shown and described.

DESCRIPTION

FIG. 1 is a front perspective view of a chef knife set, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another front perspective view of the chef knife set shown in an alternate configuration;

FIG. 9 is another front perspective view of the chef knife set shown in an alternate configuration;

FIG. 10 is another front perspective view of the chef knife set shown in an alternate configuration;

FIG. 11 is another front perspective view of the chef knife set shown in an alternate configuration; and,

FIG. 12 is another front perspective view of the chef knife set shown in an alternate configuration.

The broken lines in the drawings illustrate portions of the chef knife set that form no part of the claimed design.
